UNITED STATES PATENT OFFICE.

MELVIN CREIGHTON, OF RENSSELAER FALLS, NEW YORK.

LIGHTNING ROD.

Application filed October 19, 1921. Serial No. 508,716.

To all whom it may concern:

Be it known that I, MELVIN CREIGHTON, a citizen of the United States, and a resident of Rensselaer Falls, in the county of St. Lawrence and State of New York, have invented a new and Improved Lightning Rod, of which the following is a description.

My invention relates to lightning rods and has for its general object to provide features which in their entirety constitute a connector between the point element of the lightning rod and the conductor cable, as well as means to secure the point element in position on a roof or the like in a manner to sustain the connector and cable raised and amply protected against the ingress of rain to thereby prevent distortion of the parts with the possible result of affecting the electrical connection, due to freezing.

20 The manner in which the above and other objects are attained will clearly appear from the specific description following.

Reference is to be had to the accompanying drawings forming a part of this specification, it being understood that the drawings are merely illustrative of one example of the invention.

Figure 1 is a side elevation of an embodiment of my invention showing the same 30 as in use;

Figure 2 is a transverse vertical section on the line 2—2, Figure 1;

Figure 3 is a vertical section on the line 3—3, Figure 2.

35 In carrying out my invention in practice, in accordance with the illustrated example, I provide an element 10 which in practice is tubular and adapted to be disposed vertically above a roof or the like, said element having fitted or secured thereto a suitable point 11. A connector 12 is provided on the point receiving element 10 at the lower end and presenting a loop positioned below said element sufficiently to embrace a conductor cable A.

40 A foot 13 is provided on the point element 10 and forms a covering for the connector 12 and the adjacent portion of the cable A as well as means to secure the point element in position. The sides of foot 13 are spaced and in the illustrated example they are deflected obliquely in opposite directions as at 13^a to conform to a pitched roof, there being holes 14 in the sides at the lower portion to receive screws 15 or equivalent fastening

means securing the foot to the roof. It will be seen that when the foot 13 is fastened in position the cable A and the connector 12 are disposed directly beneath the top of the foot to be fully projected and above the roof. 60

In order to prevent the point element 10 from being separated from the foot 13, said element is formed with an outwardly directed annular flange 16 at its lower end which is positioned beneath a short neck 17 on the foot 13, the point element extending upwardly through said neck to a sufficient height to sustain the point 11 a proper distance above the roof. The connector 12 is formed of sheet metal returned on itself to 70 present arms 12^a extending into the point element 10 fitting tightly therein or made fast in any suitable manner.

In order to constitute the foot 13 a clamp, I provide a clamp bolt 18 extending transversely through the sides of the foot directly beneath the connector 12 and provided with a suitable nut 19, the tightening of which serves to tightly bind the sides of the foot against the connector 12, thereby aiding in 80 the insuring of the electrical connection between the element 10 and the cable A and at the same time serving to hold all the parts rigidly in position.

I would state in conclusion that while the illustrated example constitutes a practical embodiment of my invention, I do not limit myself strictly to the exact details herein illustrated, since, manifestly, the same can be considerably varied without departure 85 from the spirit of the invention as defined in the appended claims. 90

Having thus described my invention, I claim:

1. In a lightning rod, a point-supporting element, a looped connector suspended on said element at the lower end and positioned below the same to embrace a conductor cable, and a foot on said point element forming a means to secure said element in position as well as a covering for the connector and the adjacent portion of the cable. 95

2. In a lightning rod, a point-supporting element, a looped connector suspended on said element at the lower end and positioned below the same to embrace a conductor cable, and a foot on said point element forming a means to secure said element in position as well as a covering for the connector and the adjacent portion of the cable; together with 100 105 110

means to clamp the foot against the connector.

3. In a lightning rod, a point-carrying element, a foot thereon presenting spaced sides adapted at their lower ends to be secured to a supporting structure, and a connector positioned at the lower end of said element and beneath the foot in position to engage a cable, said connector being covered by said foot.

4. In a lightning rod, a point-sustaining element, a connector supported at the lower end of said element, and means forming a cover for said connector; together with means to clamp said cover against the sides of the connector.

5. In a lightning rod, a point-sustaining element, a foot thereon at the lower end presenting spaced sides adapted to be se-

cured to a supporting structure, means beneath said foot to connect said element to the cable, said means being covered by said foot, and transverse clamp means to bind said foot against the connector means.

6. In a lightning rod, a point-sustaining element, a foot thereon presenting spaced sides, means within said foot adjacent to the top to connect the said element with a cable, said foot forming a covering for said connector means, said foot being adapted at its lower portion to be secured to a supporting structure, and a transverse clamp bolt extending through the sides of the foot below the connecting means and adapted to bind the sides of the foot against said connecting means.

MELVIN CREIGHTON.
